UNITED STATES PATENT OFFICE

2,456,417

STEAM AND COMBUSTION GAS TURBINE

Paul Horsdal, Ottawa, Ontario, Canada

Application June 4, 1947, Serial No. 752,477

8 Claims. (Cl. 60—108)

1

This invention relates to power plants, and more particularly to steam turbines or engines.

An object of this invention is to provide power without the conventional noise of exhaust from combustion.

Another object of the invention is to provide a steam-actuated power plant of simple structure and efficient operation wherein an axially disposed water jet is arranged to impinge on a heated surface of a rotor for substantially instantaneous conversion of steam and including means for directing the steam in a plurality of streams against a stationary surface to impart a rotative driving force to the rotor.

The invention will be described with reference to the accompanying drawing in which:

Figure 1 is a more or less diagrammatic side elevational view in section, substantially on the line 1—1 of Figure 2, of a power plant in accordance with the invention, and

Figure 2 is an end elevation in section substantially on the line 2—2 of Figure 1.

In the drawing, 1 is a suitably mounted stationary annular member having an internal groove or housing 2. Within the stator 1 is mounted a rotor 3 adapted to revolve as a unit on suitable bearings 4. The rotor comprises an inner disc 5 and outer discs 6 and 7 connected together for rotation. The axial portions of discs 6 and 7 are provided with outwardly extending conical or lie portions 8 and 9 having bearing hubs 10 and 11 and forming axial chambers 12 and 13 on either side of the inner disc 5. The peripheries of the discs 5, 6 and 7 are enclosed within the housing 2.

Any suitable means are provided for heating the axial surface of disc 5 within the chamber 12. As shown, this means may comprise an axially arranged fuel jet 14 adapted to impinge on disc 5, which may be provided with a protecting baffle plate 15. The products of combustion may be exhausted through passages 16 in the disc 5, for the purpose of keeping the periphery of the rotor hot, to offset condensation of steam, and communicating passages 17 in the stator 1.

An axially arranged water jet 18 projects into the chamber 13 to impinge a stream of water onto the axial surface of the disc 5 within chamber 13. Preferably a conical cup-shaped member 19 is mounted on disc 5 to receive the water stream and to retain and maintain the water particles in heat-receiving relation to the hot axial surface of the disc. Such axial surface is adapted to be heated by the heating means 14 to a temperature which will substantially immedi-

ately convert the impinging water particles to steam.

A plurality of passages 21 are provided to conduct the steam to the periphery of the rotor. While three such passages are shown, it will be understood that two or any desired number of passages may be provided. The passages are preferably formed by recesses or grooves 20 in disc 5 each having a wide mouth portion 21 opening into chamber 13 and a restricted portion 22 enclosed by the abutting portion of disc 7. The portion 22 gradually merges into portion 21 and extends angularly therefrom to direct the steam in a partially tangential or angular direction onto the inner surface of housing 2. Preferably, valves 23 are provided in each passage 21, such valves being adapted to open to permit passage of steam when the pressure of the latter reaches a predetermined degree as, for instance, 30 pounds. The inner surface of housing 2 may be provided with semi-spherical recesses 24 to receive and deflect the steam issuing from the passages. The steam emerges through passages formed between the rotor and the stator. Such passages may be formed by providing, on the outer marginal face of the disc 7, a series of curved blades or fins 25 adjacent the outlet of each passage 21 and arranged for engagement by the steam deflected by the stator. The outer edges of the blades are in engagement with the inner lateral face of the housing 2. As the streams of steam under pressure engage the stator, a rotative impelling force is applied to the rotor to drive the same. Moreover, such force may be augmented by engagement of the streams of steam deflected by the surfaces 24 with the blades 25.

Pressure relief valves 26 may be provided for chamber 13.

Operation of the device will be apparent from the foregoing description. It will be observed that the device embodies relatively few parts and may be inexpensively operated.

It will be obvious that various changes may be made in the described details without departing from the spirit of the invention. For instance, the rotor may be of one-piece construction, having therein the various chambers and passages described.

I claim:

1. A power plant comprising an annular stator, a rotor peripherally mounted in the stator, said rotor having a pair of outer discs and an inner disc, one of said outer discs having walls forming an axial chamber, means for heating the axial portion of said inner disc, a water jet ex-

2

tending into said chamber and arranged to impinge on the axial portion of said inner disc, means forming steam passages each having an inlet in the chamber and an outlet on a surface of the stator, and blades carried by said one disc and engaging the surface of the rotor at points adjacent said passage outlet.

2. A power plant comprising an annular stator housing, a rotor peripherally mounted in the housing said rotor having a pair of outer discs and an inner disc, one of the outer discs having walls forming an axial chamber between said outer and inner discs, means for heating the axial portion of the inner disc, and a water jet extending into the chamber and arranged to impinge upon the axial portion of the inner disc, said inner disc having grooves therein forming steam passages between the inner disc and said outer disc, each passage having an inlet in said chamber and an outlet at the periphery of the discs in said housing.

3. A power plant as defined in claim 2, each of said passages having a valve therein arranged to open under a predetermined pressure.

4. A power plant as defined in claim 2, including a cup-shaped water jet receiving member axially mounted on said inner disc.

5. A power plant as defined in claim 2, wherein each of said passages has a relatively wide curved inlet portion and a relatively narrow straight portion extending angularly from said inlet portion to the outlet.

6. A power plant as defined in claim 2, including a plurality of series of curved blades on the marginal outer face of said one disc within the housing, each series of blades being located adjacent one of said outlets.

7. A power plant comprising an annular stator housing, a rotor peripherally mounted in the

housing, said rotor having a pair of outer discs and an inner disc, each outer disc having walls forming an axial chamber on the respective side of said inner disc, an axial fuel burner in one chamber arranged to heat the axial portion of the inner disc, an axial water jet in the other chamber arranged to impinge a stream of water on the axial portion of the inner disc, means forming a plurality of steam passages between one of said outer discs and the inner disc and each having an inlet in said last named chamber and an outlet on the periphery of the discs within the housing, said housing having curved steam-deflecting recesses therein, and a plurality of series of curved blades carried on the lateral face of last named outer disc and within the housing, each said series of blades being located adjacent one of said outlets.

8. A power plant comprising an annular stator, a rotor peripherally mounted in the stator, walls forming an axial chamber on the rotor, the axial portion of the rotor constituting the inner wall of the chamber, means for heating the axial portion of the rotor, and a water jet in axial alignment with and extending into the chamber and arranged to impinge on the heated axial portion of the rotor, said rotor having steam passages therein each having an inlet in the chamber and an outlet on the surface of the stator.
